DES. 2226

J. H. Stone, of Philadelphia, Penn.

Letters Patented Dec 26, Dated Dec 5, 1865.

Design for the Base of Sheet Metal Water Vessels.

The schedule referred to in these Letters Patent and making part of the same.

Ye all whom it may concern,

Be it known that J. H. Stone, of the City of Philadelphia, in the State of Pennsylvania, have invented or produced a new and original Design for the bases or lower ends of the sheet metal vessels used in dwellings, used for carrying and holding wash-water, as water carriers, pitchers and like vessels, of which the following is a full, clear and exact description, reference being had to the accompanying drawing, showing a vertical section of a water carrier, having the said base applied and making a part of this specification.

The lower ends of the sheet metal wash-water vessels, for dwellings, have heretofore been made with straight sides from top to bottom, like the common wooden buckets, but a form more useful and ornamental is required, and this is the object of my present design.

It consists in giving to these chamber vessels a recessed or necked base, substantially of the exterior form or shape shown in the drawing, the part or portion of the vessel which is above the said necked or recessed base, being of any suitable form or shape, that the particular requirements of the vessel may render proper.

In the said drawing A.B. is the new base applied to a water carrier. It consists of two main parts, viz. the convex or curved portion $a^{\frac{1}{2}} b$ and the outward flared portion $a^{\frac{1}{2}} b^{\frac{1}{2}}$. The straight sides of the body of the vessel join the upper end of the convex portion $a^{\frac{1}{2}} b$, and the lower end $b^{\frac{1}{2}}$ of the flared portion $a^{\frac{1}{2}} b^{\frac{1}{2}}$ forms the foot of the base, whilst the narrower or smaller end of the said flared portion connects with the foot of the convex portion $a^{\frac{1}{2}} b$; and thus connected together, the two said parts form, under the body of the vessel, a necked or recessed base, A.B. which is ornamental and appropriate, as seen in the drawing.

DES. 2226

2

What I claim is my invention and desire to secure by letters
Patent is -

The recessed or notched base A. B herein set forth, as a design
for the lower ends of sheet metal wash water vessels for dwellings.
